PROTECTED BLADE

Henry J. Gaisman, Hartsdale, N. Y., assignor to
 Gillette Safety Razor Company, Boston, Mass.,
 a corporation of Delaware

Application February 19, 1934, Serial No. 711,833

4 Claims. (Cl. 206—16)

This invention consists in a safety razor blade having a new and improved protective cover so designed as to insure it against becoming dulled or rusted up to the time that it is actually presented to the razor by the user.

In handling safety razor blades under commercial conditions of distribution and storage and in the more or less casual handling by the user the extremely keen fine edge of the blade is likely to become dulled by being brought into contact with its wrappings or other objects before the blade is actually clamped in its shaving position in the razor. On this account the best and more skillful efforts of the manufacturer in sharpening blades are often brought to naught because of the difficulty of preserving intact the very fragile and delicate structure of a blade edge which has been brought to the keenest possible shaving condition. Safety razor blades are also subject to rusting and corrosion while in transit and in storage, particularly when marketed in the tropics. The protected blade of my invention is rendered practically proof against rusting and corrosion by the novel cover of my invention.

With these conditions in view, an important feature of the present invention consists in a novel cover of waxed paper or the like comprising sheets shaped to permit the presentation of the protected blade to the razor and projecting outside or beyond the cutting edge of the blade and protecting it from direct contact until such time as it has been fully presented in or upon shaving position in the cap or guard of the safety razor by the user. I have discovered that such a protective cover may be made to adhere to one or both surfaces of a safety razor blade in a clinging or slipping manner of engagement, so that it is readily removable by being drawn or slipped off the blade.

Preferably and as herein shown each blade is provided with protective cover sheets secured to its opposite surfaces and with the edges of the sheets unjoined and projecting beyond the sharpened edges of the blade. The cover thus employed to protect the blade is provided with a tab or other portion whereby the user may seize the cover and withdraw it from the blade.

The cover of my invention is particularly adapted for thin flexible blades, internally apertured to receive the usual blade positioning projections of a safety razor. The sheets of the cover are longitudinally slotted in registration with the apertures of the blade which they enclose. The slot is of such dimensions and so located as to

clear the blade-locating projections of the razor, thus, in the first place, adapting the protected blade to be presented to the razor and located by its projections, and in the second place, retaining the blade in the razor while the user withdraws the protective cover therefrom. It will be noted that the sharp edges of the blade are thus protected until after the blade has been presented in its final location in the razor and is no longer liable to be damaged by contacting with its wrapping or with any part of the razor to the serious detriment of its keenness.

Particular features of my invention are a slide-off cover or package for the blade; a cover adapted to provide a protecting margin alongside a cutting edge to defend such edge; a cover, the continuity of which is so interrupted as to permit a blade adapted to be connected to a blade holder to be located thereon without removing the cover and to permit the cover to be withdrawn while leaving the blade connected with its holder.

These and other features of the invention will be best understood and appreciated from the following description of a preferred embodiment thereof, selected for purposes of illustration and shown in the accompanying drawing, in which,—

Fig. 1 is a plan view of one type of safety razor blade in connection with which the invention may be employed;

Fig. 2 is a plan view of the cover for such a razor blade;

Fig. 3 is a plan view of the blank which may be folded to form the cover shown in Fig. 2;

Fig. 4 is a view in cross-section of a sheath-like form of cover;

Fig. 5 is a fragmentary view in side elevation of two protected blades in superposed relation; and

Fig. 6 is a view in perspective showing the protected blade in position upon the cap of the razor with its cover partially withdrawn.

It will be understood that my invention is in no sense limited in its use to any specific type of safety razor blade but is of general application to any internally apertured or perforated blade. The particular blade shown in the accompanying drawing represents merely one double-edge safety razor blade of well-known commercial type. The blade 10 is of thin flexible steel sharpened at its opposite edges 12 for cutting. The blade is provided with three spaced apertures 14 adapted to receive the projecting blade-locating studs of one of the clamping members of the safety razor in which it is to be used. As herein shown the apertures 14 have curved end walls and oppo-

sitely-disposed inwardly extending tongues in their longitudinal edges. The apertures are therefore adapted to engage and accurately locate the blade upon blade-locating studs which are 5 cylindrical in cross-sectional contour or which correspond in contour to the configuration of the apertures. The blade-locating studs which co-operate with the apertures 14 may be arranged upon the cap or upon the guard of the razor, 10 or partly upon one of these members and partly upon the other.

It is proposed to enclose each blade 10 in a protective cover of thin sheet material, such as 15 waxed paper, of the general character shown in Fig. 2 which may be formed by folding on an intermediate transverse line the flat blank shown in Fig. 3. The folded blank presents a cover having side portions 16 spaced from each other by a longitudinal slot 18 which opens out through 20 one end of the cover. At the other end of the cover the side portions 16 are joined by an end portion 20. A rectangular tab 22 is cut in the cover adjacent to the fold vertex thereof and is normally directed at its inner end toward the slot 18, although it may be bent outwardly into the position shown in Fig. 6, so that it may be 25 grasped conveniently by the user, as will presently appear.

The cover is somewhat longer than the overall 30 length of the blade 10, so that the latter may be completely enclosed therein except for the portion exposed through the slot 18 and this in the present instance includes the body of the apertures 14. The free edges of the two parts of the 35 cover overlap and register with each other and extend beyond or outside the cutting edges 12 of the blade. The lapped edges of the cover, therefore, serve to defend or protect the sharpened cutting edges of the blade. The cover may be 40 conveniently formed of grease-proof material, such as waxed paper and the blade 10 may be suitably treated with protective layers of oil or other rust-preventing coating which, besides preventing the blade from rusting, causes the 45 cover to adhere to the surface of the blade and to be maintained in slipping engagement therewith.

The cover may be either open along its outer 50 longitudinal edges, or it may be formed as a bag or sheath 26 as shown in Fig. 4. The cover shown in Fig. 4 is similar to that of Figs. 2 and 3 and is provided with a longitudinal slot 28, but its longitudinal edges are secured together instead of being separate and disposed in overlapping registration as in Figs. 2 and 6.

One sheet of the protective cover is provided 55 with the inwardly extending tab 22 and the other with a tab 24 which originally projects into the closed end of the slot 18. It is contemplated that the protected blades will be assembled in a container or package one above the other as suggested in Fig. 5. The user may withdraw these 60 blades from the package one by one, selecting always the uppermost blade in the stack. For 65 this purpose the tab 22 may be folded outwardly into the position shown in Fig. 6. This may be done by the user as he withdraws the blade or it may be done by the tab 24 of the uppermost blade as it is withdrawn from the stack. To this 70 end, the tab 24 may be folded so that it extends forwardly toward the end of the protected blade in position to catch upon the tab 22 of the blade cover beneath it during its movement of withdrawal.

75 The slot 18 in the cover is of sufficient width

freely to clear the blade-locating projections from the razor in which the blade is to be used so that the cover may be withdrawn by an endwise movement without in any way coming in contact with the projections. The operation of withdrawing the cover is suggested in Fig. 5 in which is shown a cap 28 provided with a central threaded stud 30 and a pair of spaced blade-locating studs 32, one on each side of the threaded stud. The cap 28, as will be well understood, is employed in 10 cooperation with a guard member having holes or bores for the reception of the three studs and a threaded handle cooperating with the threaded stud 30 to draw the cap and guard into a clamping relation in which the thin flexible blade is 15 supported on both sides adjacent to its cutting edge.

It will be seen that the protected blade with its cover may be placed upon the studs of the cap 28, being located thereby accurately in shaving position and so held by the engagement of the studs with the walls of the apertures 14. When the protected blade has been so positioned the user has only to grasp the tab 22 or the end 20 of the cover and draw it endwise, thus sliding the 25 cover from off the blade and leaving it free upon the cap and ready for shaving. The protected blade of course may be presented to the cap either end about and the adhesive engagement of the grease or oil upon the blade does not interfere 30 with the withdrawing of the cover but permits it readily to slide from the blade. It will be noted, moreover, that by thus presenting such blade its edges are safeguarded against the possibility of being dulled by contact with any part 35 of the razor or any part of the cover and that the blade is exposed for the first time after it has been safely located in a part of the razor in which it is to be used.

The modified cover shown in Fig. 4 is similar 40 to that already described except that its longitudinal edges are united so that the cover as a whole is of sheath form instead of having its longitudinal edges free and unconnected. The blade may be inserted in this sheath form of 45 cover and the cover removed in the same manner as already described in connection with the folded form of cover.

It is to be understood that the invention is 50 equally applicable to a blade having a single cutting edge and also to a blade having a single blade-locating aperture as distinguished from a blade like that shown which has a plurality of apertures.

The subject matter of the present application 55 is disclosed but not claimed in my prior Patent No. 1,851,043, granted March 29, 1932.

Having thus described my invention what I claim as new and desire to secure by Letters Patent of the United States is:—

1. A protected blade internally apertured for engagement with the locating projections of a safety razor and having a cover sheet attached to one surface and extending beyond the cutting edge of the blade and which is longitudinally slotted to clear such projections when the blade is placed in the razor, thereby permitting the cover sheet to be drawn off the blade by endwise movement.

2. A protected double-edged blade internally apertured to receive the locating projections of a safety razor and covered by a U-shaped cover sheet on each surface extending beyond the cutting edges of the blade and one end of the blade. 75

and adapted to be drawn off the blade while the latter is held in position in the safety razor.

3. A protected double-edged blade internally apertured to receive the locating projections of a safety razor and provided with a cover sheet on each surface having a connecting portion covering one end of the blade and spaced side portions covering the cutting edges of the blade and separated at their free ends to clear the projections of the razor, thereby permitting the cover sheets to be simultaneously removed from the blade by endwise movement while the blade is held in the razor.

4. A protected double-edged blade for safety razors, having a blade-locating perforation within its periphery, and covered by protective sheets having a connecting portion folded to enclose one end of the blade and side portions extending therefrom, shaped to overlie the edges of the blade and spaced to clear the perforation of the blade, thereby permitting the protective sheets to be pulled endwise from the blade to expose its edges while the blade is positioned in the razor by a projecting member which enters said blade-locating perforation.

HENRY J. GAISMAN.
